(57) **CLAIM**

The ornamental design for a bench for housing pets, as shown and described.

DESCRIPTION

FIG. 1 is a perspective view of a bench for housing pets showing our new design.

FIG. 2 is a front side view thereof.

FIG. 3 is a back side view thereof.

FIG. 4 is a left side view thereof.

FIG. 5 is a right side view thereof.

FIG. 6 is a top plan view thereof; and,

FIG. 7 is a bottom plan view thereof.

In each of the drawing figures, surface shading is used to clearly show the character and contour of all surfaces of the 3-dimensional aspects of the design. The broken lines in the figures depict portions of the bench that form no part of the claimed design.
